(57) **CLAIM**

The ornamental design for a spherical utility hook, as shown and described.

DESCRIPTION

FIG. 1 is a front elevational of a utilitarian hook in accordance with the present design;

FIG. 2 is a side elevational view of said utilitarian hook, the side of the utilitarian hook not shown being a mirror image of the side shown in this view;

FIG. 3 is a top plan view of said utility hook;

FIG. 4 is a bottom plan view of said utilitarian hook;

FIG. 5 is a back elevational view of said utilitarian hook; and,

FIG. 6 is a sectional view taken through the vertical center of FIG. 1.
